A. G. Burns ATTORNEY

UNITED STATES PATENT OFFICE

WILLIAM C. RASTETTER, OF FORT WAYNE, INDIANA

TABLE TOP

Application filed November 22, 1926. Serial No. 149,948.

This invention relates to improvements in table tops, particularly that type wherein a covering of leather or other suitable material is permanently applied to form the top surface of the table, and the object of the invention is to so construct the table top and apply the cover therefor in such manner as to insure smoothness and neatness of the covering throughout its exposed surface, and 10 to completely conceal the marginal edges of the sheet forming the covering. This object is accomplished by the construction illustrated in the accompanying drawings, in which:—

15 Fig. 1 is a plan view of a table top embodying the invention, portions being broken away; and

Fig. 2 is a fragmentary cross section of the table top upon a larger scale than Fig. 1.

20 The characters appearing in the description refer to parts shown in the drawings and designated thereon by corresponding characters.

The invention consists of a table top 25 formed with a marginal frame 1 of wood or other suitable material, upon which is secured a top plate 2, preferably formed of fibre board, wood or other stiff material, there being a narrow strip 3 interposed between the top plate 2 and the frame 1 along 30 the inner margin of said frame. The plate and strip are secured in fixed relation with the frame by nails 4. The margin 5 of the plate 2 overhangs the strip 3, and a space 35 6 is left between the top of the frame and the margin 5 of the plate entirely around the outer edge of the table top. The plate 2 has superimposed thereon a sheet 7 of padding material, and a cover 8 of leather, imitation leather or suitable fabric is laid over the padding, the margin 9 of the cover extending over the margin of the plate and into the space 6 between the plate 2 and frame 1. The margin 9 of the cover is 45 turned by applying pressure thereto with a suitable instrument so as to force it into the space 6 where it is held permanently wedged in place. In this manner the edge of the plate is concealed by the cover 8 as well as the padded top of the plate, leaving only the

cover and the frame exposed to view. By making the strip 3 of less thickness than that of the cover, the margin of the cover, when forced into the space 6 is held firmly between the plate and frame, so that nailing, 55 gluing, and other securing means usually employed to secure the cover is obviated.

In thus constructing the invention economy in manufacture and neatness in appearance are effected.

What I claim is:—

1. A top for a table comprising a wooden marginal frame; a thin strip narrower than the piece of which the frame is formed, and extending on the top of the frame along the inner edge thereof; a top-plate of stiff material covering the top of the frame and positioned upon said strip with its margin overhanging said piece, there being a space extending entirely around the table between the margin of the plate and the top of the frame; a padding superimposed upon said plate; and a cover of sheet material extending over the padding, the margin of said cover extending over the edge and secured 70 under the margin of said plate in the space between the plate and frame.

2. A table top having a frame formed of a strip of wood constituting the outer marginal support thereof; a superimposed strip 80 narrower than the strip forming the frame, disposed thereupon adjacent the inner edge thereof; a top plate of stiff material covering the top of the frame and positioned upon said superimposed strip with its margin lying above said frame strip and spaced from the top of the frame; and a covering of flexible sheet material extending over the top and edges of said plate with its margin inserted beneath the margin of the plate into 85 the space between the plate and frame.

In testimony whereof I affix my signature.

WILLIAM C. RASTETTER.
